UNITED STATES PATENT OFFICE.

HUGH ALISON REYNOLDS, OF ANNISTON, ALABAMA.

TYING DEVICE.

1,139,721.

Specification of Letters Patent. Patented May 18, 1915.

Application filed March 4, 1914. Serial No. 822,425.

To all whom it may concern:

Be it known that I, HUGH ALISON REYNOLDS, a citizen of the United States, residing at Anniston, in the county of Calhoun 5 and State of Alabama, have invented a new and useful Tying Device, of which the following is a specification.

The present invention appertains to tying devices for bundles or packages, and aims to 10 provide a novel and improved appliance of that character.

It is the object of the present invention to provide a unique tying device, which may be conveniently and effectively employed for 15 tying or binding a bundle or package of letters or other mail matter, in order that the bundle may be handled or transmitted, without danger of the bundle becoming loosened.

Another object of the present invention is 20 to provide a simple and inexpensive device of the nature indicated, which may be applied to a bundle or package, to tie or bind the same without knotting the tying or binding element.

25 A further object of the present invention is to provide a device of the character indicated, which may be conveniently employed with various sizes of bundles or packages, to eliminate the use of the ordinary twine 30 for tying together bundles of mail matter, and the present device being devoid of any gripping or locking members, or the like, which are objectionable.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, can be made within the scope of what is claimed, without departing from the spirit of the invention.

45 The invention has been illustrated in its preferred embodiment in the accompanying drawing, wherein:—

Figure 1 is a perspective view of the tying device, a portion of the cord or flexible binding element being broken away. Fig. 2 is a perspective view of the tying device as applied to a bundle or package.

50 The present device embodies only two parts, one of which is a rigid frame, and the other of which is a cord or flexible binding element attached permanently to the frame.

The frame is constructed from wire stock, although it may be otherwise manufactured, and embodies a pair of parallel side bars 1, forming the body or base of the frame, and 60 having the angularly extended portions 2 at one end, forming the end piece or head of the body or frame. The other ends of the side bars 1 are connected by an inwardly curved cross piece or yoke 3, while the angular or end members 2 are connected by a re-entrant V-shaped member or yoke 4 having its crotch formed with an eye or loop 5. The diagonally arranged arms or limbs of the yoke 4 form, with the angular or end 70 pieces 2, projections or horns 6.

The side bars 1 are relatively long, while the end pieces or members 2 are relatively short, whereby the bundle of letters or other articles, may be placed upon the body or 75 base comprising the side bars 1, with one end or side of the package or bundle resting against the end members 2 and the yoke 4, as clearly delineated in Fig. 2. Thus, the body of the frame is adapted to rest against 80 one face of a bundle of articles, while the angularly extended end portion of the frame or body is adapted to rest against certain edges of the articles.

The other part or element of the device 85 constitutes a cord or flexible binding element 7 of suitable length, and having one end permanently tied or secured to the eye or loop 5 at the crotch of the yoke 4 between the 90 projections or horns 6.

In employing the present devices for binding or tying a package or bundle, say, for example, a bundle of letters, as illustrated in Fig. 2, the bundle of letters are placed upon the frame, with one end or side of the 95 bundle resting against the end members 2 and yoke 4 as illustrated in full and dotted lines, respectively, in Fig. 2. One face of the bundle rests against the side bars 1 and the yoke 3, it being noted that the frame 100 is engaged over one corner of the bundle to rest against one end or side and one face thereof. The frame may be readily held in the hand, while the bundle is applied thereto, and the cord 7 is then wound around the 105 bundle and frame any suitable number of times, according to the size of the bundle and the length of the cord. Then, when the bundle and frame are tightly wrapped by the cord, the free or terminal portion of the 110 cord may be slipped between the letters in any suitable manner to cause the letters to

grip and hold the free portion of the cord. It may be preferable to slip the free portion of the cord over one or the other of the projections or horns 6, so as to engage over the corresponding arm of the yoke 4, and then to draw the said free portion of the cord between the corresponding corner portions of certain of the letters, as designated at 8 in Fig. 2, whereby the free portion of the 10 cord will be gripped tightly between the letters, to hold the free portion of the cord in place, without the necessity of tying the free end of the cord or flexible binding element. The bundle or package may thus be held intact, during handling and transmission, without the liability of the tying device opening under the conditions to which the package or bundle is subjected. If the free portion of the cord is engaged over one of 15 the projections or horns 6, it will prevent the cord from being drawn out of position or off of the package or bundle, when the free portion of the cord is drawn between the letters. The curved yoke 3 and the V-shaped yoke 4 also enable the respective corner portions of the package or bundle to be drawn inwardly when the cord or flexible element is wound tightly, to secure the 20 tying device against displacement.

25 30 As is obvious, the present tying device may be repeatedly employed, it only being necessary, when removing the tying device from a bundle or package, to withdraw the free portion of the cord or binding element 7 from between the letters or articles and over the corresponding projection or horn 6, which will permit the tying device to drop from the package or bundle. The present device is of utmost simplicity, embodying 35 only two elements, the frame being readily fashioned from wire, and being inexpensive to manufacture, while the cord 7 is still less expensive, and may be replaced when worn out.

40 45 From the foregoing, taken in connection with the drawing, the other advantages and

capabilities of the present device will be obvious, without further comment.

Having thus described the invention, what is claimed as new is:—

50 1. A tying device embodying a body adapted to rest against one face of a bundle of articles and having an angularly extended portion to rest against certain edges of the articles, and a flexible binding element 55 attached to the body and adapted to be wrapped around the bundle and body, the said angularly extended portion having means for the engagement of the binding element thereover to enable the binding element to be drawn between the articles. 60

2. A tying device including a frame comprising a body having an angularly extended end adapted to be applied over the corner of a bundle, said angularly extended end 65 having a reentrant V-shaped portion, and a flexible binding element attached to the frame. 65

3. A tying device embodying a frame including a pair of side bars having angularly 70 extended portions at one end, a yoke connecting the other ends of the side bars, and a reentrant V-shaped yoke connecting the said angularly extended portions, and a flexible binding element attached to the said 75 frame. 75

4. A tying device embodying a frame including a pair of side bars having angularly extended portions at one end, a yoke connecting the other ends of the side bars, and a 80 reentrant V-shaped yoke connecting the said angularly extended portions and having an eye in its crotch, and a flexible binding element attached to the said eye. 80

85 In testimony that I claim the foregoing as my own, I have hereto affixed my signature in the presence of two witnesses.

HUGH ALISON REYNOLDS.
